CLAIM

The ornamental design for a machine for inserting paper sheets into envelopes, as shown and described.

DESCRIPTION

FIG. 1 is a front elevational view of a machine for inserting paper sheets into envelopes showing my design;

FIG. 2 is a top plan view thereof;

FIG. 3 is a left side elevational view thereof;

FIG. 4 is a right side elevational view thereof;

FIG. 5 is a perspective view thereof; and

FIG. 6 is a rear elevational view thereof.
